UNITED STATES PATENT OFFICE.

SIMON LAKE, OF MILFORD, CONNECTICUT.

APPARATUS FOR CONSTRUCTING CONDUITS AND THE LIKE.

1,409,732.

Specification of Letters Patent. Patented Mar. 14, 1922.

Application filed May 5, 1920. Serial No. 379,082.

To all whom it may concern:

Be it known that I, SIMON LAKE, a citizen of the United States, residing at Milford, in the county of New Haven and State 5 of Connecticut, have invented a certain new and useful Improvement in Apparatus for Constructing Conduits and the like, of which the following is a full, clear, and exact description.

10 This invention relates to the forming of structures of concrete and the like, and, particularly, to the forming of tubular structures such as sewers, drains and conduits.

Concrete structures of this nature are now 15 generally made by building proper forms, usually of wood, and positioning them in a prepared trench, and then pouring the concrete or other plastic material around them, natural heat and evaporation of the moisture in the material being depended upon 20 to set it. This, especially in cool weather, is very slow, so that great numbers of forms are required in order to perform the construction work with any degree of rapidity, 25 it being unwise to remove any of the forms before the part of the structure supported thereby has set to comparative hardness.

The object of this invention is to accomplish the construction of such structures in 30 a rapid and inexpensive manner to the end that considerable lengths of sewers and the like may be formed from day to day with the same forms, without the customary loss of time due to waiting for the setting of the 35 material.

The invention consists in apparatus for forming sewers and the like structures, whereby, as the work progresses, the plastic material may be supported in desired form 40 and at the same time subjected to the influence of artificial heat whereby its setting is expedited; or the artificial heat may be applied after the workmen have left for the day, whereby by morning the plastic will 45 have become sufficiently hard to remove the supporting forms, thus admitting of their being again immediately used and consequently not interfering with the progress of construction, all as I will proceed now to 50 explain and finally claim.

In the accompanying drawings, in the several figures of which like parts are similarly designated, Figure 1 is a longitudinal section showing a structure being made with 55 the devices of my invention. Fig. 2 is a

transverse section taken in the plane of line 2-2, Fig. 1. Fig. 3 is a longitudinal section of one of the form members, drawn to a smaller scale, taken in the plane of line 3-3 of Fig. 4. Fig. 4 is a section taken in 60 the plane of line 4-4, Fig. 3. Fig. 5 is a fragmentary sectional elevation showing various details of construction.

In the forming of structures according to my invention, I dig a trench of the usual 65 type, provided with sheeting 1 if necessary, and at the bottom thereof I sink posts 2 to the proper depth to serve as stable supports for the structure. In the trench thus formed I lay a course of concrete 3 of the proper 70 thickness, and upon this I support the form members 4, these members 4 being placed end to end and securely fastened together in alignment by means of ears 5 and bolts 6, or the like. Upon the exposed edges 7 of 75 these members are laid wedge-shaped key pieces or members 8 upon which in turn are supported the form members 9, similar in structure to the members 4. The members 4 and 9 are then securely clamped together 80 and held in rigid adjustment and alignment by means of eyes 10 to which are connected rods 11 joined by turnbuckles 12 or the like tensioning devices, whereby the necessary 85 tension may be provided to obtain the desired rigidity. The form members 9 are also provided with ears 5 and bolts 6 for connecting them longitudinally.

Above the members 9 and in spaced relation thereto are supported templates 13, their 90 outer edges 14 resting against battens or blocks 15 secured to the sheeting 1, and their adjacent edges 16 turned up and spaced apart by spacing members 17, so as to form a trough through which concrete may be 95 poured to fill the space around the form members, and affording an opening through which the thus poured concrete may be tamped down, if desired. The templates 13 are reinforced so as to retain their proper curvature by means of angle-bars 18 arranged at intervals throughout their length, the outer ends of these bars resting upon the battens or block 15.

After the desired length of forms has 105 been set up, and the space formed between them and the trench walls and the templates filled with concrete or other plastic material, the form may be heated by steam, hot water, or the like heating medium, and for 110

accomplishing this I construct the various form members as hollow shells formed of spaced-apart plates, the spaces 19 thus provided being adapted to receive the heating 5 medium.

Extending longitudinally of the members 4 and 9 and at their uppermost portions are steam or the like pipes 20 supported in spaced relation to the outer and inner shells 10 of the members by collars 21 and screws or rivets 22, and these pipes are provided with plug or other valves 23 operable from within the form whereby the steam or the like may be admitted to or cut off from the spaces 19 15 of the individual members at will. Drains 24 are provided at the lowermost portions of the members whereby the water of condensation or other condensed or cooled heating medium may escape from the spaces 19 20 to the atmosphere.

The pipes 20 and drains 22 are provided with tapered plug and socket joints 25 and 26, respectively, at the abutting ends of the form members, as shown clearly in Fig. 5, 25 whereby when the members are drawn together longitudinally a fluid-tight joint will be provided, and a continuous conduit formed from end to end of the form as set up.

30 As hereinbefore stated, after the concrete has set to the desired degree of hardness, the heating medium is turned off at the source, the wedge-shaped key members 8 and the spacers 17 removed, and the forms collapsed 35 and removed, to be set up again farther along the trench.

In order that the key members 8 may be easily withdrawn from between the edges of the form members 4 and 9, I provide them 40 with eyes 27 to afford a means of leverage.

If desired, the end members of the form may have the pipes 20 closed, as shown at 28 in Fig. 1.

It will be apparent that this invention is 45 of marked value in doing concrete work and the like in freezing temperatures, in which case the materials may be mixed with hot water and while still warm poured around the forms, the steam for heating the forms 50 being turned on within a reasonable time thereafter.

Experiments have shown that this drying by artificial heat in no wise arrests the continued setting of the material after such heat 55 has been removed, and therefore does not diminish the ultimate strength of the structure so formed.

I do not wish to be understood as limiting my invention to the particular embodiment

shown and described, as it is obvious that 60 various changes in details of construction and arrangement of parts are permissible within the spirit of the invention and the scope of the following claims.

What I claim is:—

65 1. In an apparatus for constructing conduits and the like, a collapsible form composed of a plurality of co-operating members formed of spaced-apart plates, means for holding said members in proper cooperative relation during the application of a plastic substance thereto, and means for introducing a heating medium into the space between said plates.

70 2. In an apparatus for constructing conduits and the like, a collapsible form composed of a series of form sections laid end to end, means for maintaining the sections in their position, means for introducing a heating medium to said sections, said means 75 including a pipe in each section and joints at the ends of the sections whereby said pipe may be made continuous throughout said series, and means in each section for controlling the admission of said heating medium thereto.

80 3. In an apparatus for constructing conduits and the like, a collapsible form composed of a series of sections laid end to end to produce a continuous form, each section 85 composed of a plurality of members formed of spaced-apart plates, means for introducing a heating medium into the space between said plates and for controlling such introduction, means for conducting said heating 90 medium from one section to another, and means for collapsing said sections whereby 95 they may be removed from the structure formed on them.

4. In an apparatus for constructing conduits and the like, a collapsible form composed of a plurality of similar double-walled members, each member provided with means for connecting it with a member disposed upon it and other members at its ends, a 100 pipe carried in the space between the walls of the member and adapted to convey a heating medium, means projecting through the inner wall of the member for controlling the flow of heating medium from said pipe 105 to the space between the walls of the member, and means for draining said space.

110 In testimony whereof I have hereunto set my hand this 4th day of May A. D. 1920.

SIMON LAKE.
